UNITED STATES PATENT OFFICE.

LOUIS FOSTER JACKSON, OF STARKVILLE, MISSISSIPPI.

TIMER-LUBRICATING DEVICE.

Application filed December 8, 1922. Serial No. 605,291.

To all whom it may concern:

Be it known that I, LOUIS FOSTER JACKSON, a citizen of the United States, residing at Starkville, in the county of Oktibbeha and State of Mississippi, have invented certain new and useful Improvements in Timer-Lubricating Devices, of which the following is a specification.

My invention relates to means for lubricating the timer of a Ford automobile, by passing air laden with atomized or vaporized oil from the crank case into the timer shell.

An important object of the invention is to provide a device of the above mentioned character, which will supply the atomized oil to the interior of the shell of the timer, whereby it may be supplied to the roller, stationary contacts, and portions of the shell engaged by the roller, thereby maintaining these parts properly lubricated and preventing the wear which frequently occurs, when oiling of the timer is neglected.

A further object of the invention is to provide a device of the above mentioned character which may be manufactured as an attachment to be applied to the timer shell of the Ford automobile or any use, or may be made as a part of the timer shell.

Other objects and advantages of the invention will be apparent during the course of the following description.

In the accompanying drawings, forming a part of this specification and in which like numerals are employed to designate like parts throughout the same,

Figure 1 is a side elevation of the device embodying my invention,

Figure 2 is a perspective view of the device and timer shell removed, and,

Figure 3 is a detail section through the coupling element.

In the drawings, wherein for the purpose of illustration is shown a preferred embodiment of my invention, the numeral 5 designates the timer shell of the Ford timer, as used upon the ordinary Ford automobile. This timer shell is detachably held in place in the usual manner. The timer shell carries contact segments 6, electrically connected with the binding posts 7, which lead to the spark plugs, as is well known. The circuit is made at each contact segment 6 by the usual roller, traveling within the timer shell, as is well known.

It is well known to those who operate Ford automobiles, that unless oil, preferably a light oil, is constantly supplied to the interior of the timer shell, that the operating parts of the timer shell quickly deteriorate or become destroyed. There is an opening formed in the timer shell through which oil may be readily passed. This oil serves to lubricate the contact roller and the contact segments, the circuit being closed as the roller is passing over the segments.

In accordance with my invention, I provide means whereby the air within the crank case, which is laden with atomized or vaporized oil is caused to pass to or circulate within the timer shell, thus supplying a constant lubrication, in a highly efficient manner, to the operating parts of the timer, including the roller and contact segments.

In accordance with my invention I provide a coupling element 8, preferably in the form of a tubular cone, provided at its open end with a cylindrical flange 9, to fit snugly over the flange 10, formed upon the usual tubular neck 11, which leads into the crank case of the Ford automobile. This is the usual tubular neck through which oil is passed into the crank case of the engine. The flange 9 preferably forms a substantially air tight connection with the flange 10. Connected with the tubular coupling 8 is a flexible tube 12, of any well known or preferred construction, and this tube has one end thereof passed through the usual oil supply opening 13, formed in the timer shell 5. It is preferable that the tube 12 have an air tight fit within the opening 13.

With the parts arranged as shown in Figure 1, it will be seen that as the air is circulating in the crank case of the engine, due to the breathing action of the pistons, such air laden with the atomized or vaporized oil, is forced through the tube 12 and into the shell 5. There is a constant circulation of this air laden with the atomized oil from the crank case to the timer shell 5. The air in the timer shell 5 is therefore saturated or laden with the atomized oil, and this oil is therefore brought into contact with the roller and contact segments and other operating parts of the timer. It has been found that this is a very satisfactory manner of lubricating these parts, as it renders it certain that they are constantly retained suitably lubricated, but ex-

cess of oil is not supplied thereto, which might produce the usual coating or clogging of the operating parts of the timer.

It is to be understood that the form of my invention herewith shown and described is to be taken as a preferred embodiment of the same, and that various changes in the shape, size, and arrangement of parts may be resorted to without departing from the spirit of my invention or the scope of the subjoined claims.

Having thus described my invention, what I claim is:

1. Means for supplying oil laden air from the crank case of an automobile to the timer shell, comprising a tube having means of communication with the crank case to receive the oil laden air therefrom, said tube having its outlet end leading into the timer shell to discharge the oil laden air therein, said outlet end being uncovered whereby the oil laden air may pass freely to all parts interiorly of the shell including the contact segments.
2. The combination with the tubular neck of the crank case of an internal combustion engine and the timer shell of said engine, of

a tubular coupling detachably mounted upon the tubular neck, and a tube connected with the tubular coupling and having its discharge end in communication with the interior of the timer shell, said tube having the outlet end of its bore uncovered within the timer shell whereby the oil laden air may pass freely to all parts interiorly of the shell including the contact segments.

3. The combination with the tubular neck of a crank case of an internal combustion engine and the timer shell of the engine, said timer shell having an oil receiving opening, a flexible tube having one end thereof held within the receiving opening, and a tapered coupling secured to the opposite end of the tube and having its enlarged end adapted to effect a substantially air tight engagement with the tubular neck, said flexible tube having the outlet end of its bore uncovered within the timer shell whereby the oil laden air from the crank case may pass freely to all parts interiorly of the shell including the contact segments.

In testimony whereof I affix my signature.

LOUIS FOSTER JACKSON.
